UNITED STATES PATENT OFFICE

2,663,778

ELECTRIC CIRCUIT PROTECTOR

William D. Matthews, Atlanta, and Thomas E. Curtis, Hampton, Ga., assignors to Southern States Equipment Corporation, a corporation of Georgia

Application February 14, 1951, Serial No. 210,810

10 Claims. (Cl. 200—126)

1

The object of this invention is to prevent one conductor of an electric circuit from remaining charged after another conductor has been open-circuited, as by the blowing of a fuse.

One purpose is to provide a grounding means to prevent a two-phase or a three-phase electric motor from continuing to operate on a single phase after the blowing of one of the fuses through which the motor receives power; another purpose is to provide a simple, low cost device for this use; another purpose is to make a device which applies the force of the hammer-blow of a falling fuseholder directly to releasing the grounding members so they may function; another purpose is to provide a simple means to prevent an accidental grounding operation while blown fuselinks are being replaced; and other purposes will be evident from the specification and claims.

The present device is somewhat similar to that shown in U. S. Patent No. 2,089,387, but the present device has fewer parts, it can be made at lower cost and it functions more efficiently. The invention can be used in conjunction with repeater fuses or with only a single dropout fuse in each conductor, and the operation is the same in each case. In the present specification and drawings single fuses are shown.

In the drawings, Figure 1 shows a front view of three dropout fuses with one form of this invention installed below the fuses; Figure 2 is a side view on the plane 2—2 in Figure 1; Figures 3, 4, 5, and 6 are side views of the latch 15 on the sectional plane 3—3 in Figure 1; Figure 7 is a large scale front view of box 21 with the cover removed; and Figure 8 is a similar side view of the box, on the section line 8—8 in Figure 7.

Referring to Figures 1 and 2, the support 1 holds two insulators 2, 3 with a conductive terminal on each insulator, and an expulsion-tube fuseholder 4 hinged at terminal 5 and latched into position at terminal 6. A grounding contact 7 is secured to terminal 5. Three conductors A₁—A₂, B₁—B₂ and C₁—C₂ constitute the three-phase circuit which the three dropout fuses protect. The dropout fuses are all alike. The term conductor in the specification and claims is understood to designate the fuselink inside of each fuseholder and also all conductive members which normally are electrically connected with such fuselink.

Spaced below the fuseholders and rotatably supported, as by angle clips 8, 8, 8, are the grounding bar 9 and the operating bar 10. Secured to the grounding bar 9 are three ground-

2

ing members 11—11, which are movable into and out of contact with grounding contacts 7—7, respectively. Secured to operating bar 10 are three trip members 12—12, each being in position to be struck by its respective fuseholder when the fuseholder drops by gravity to its open-circuit position as shown by dotted lines in Figure 2.

Also secured to grounding bar 9 is the curved reset crank 13 with pivot 14 at its swing end. See Figures 3, 4, 5 and 6. Supported on pivot 14 is latch 15 which is partially box-shaped with two sides cut away at recesses 16, with a hole in the front side, with a reset ring 17 and a release ring 18. Collar 19 is secured to operating bar 10 and it has a projection 20 for engagement with the upper edge of the hole in latch 15, as shown in Figures 1 and 5.

Intermediate between the two ends of each of 20 said bars 9 and 10, is the housing 21, which is suitably held as by support 22. See Figures 2, 7 and 8. Spring shaft 23 passes through box 21 and about it is spring collar 24 which is secured to shaft 23 by screw 25. One end of operating 25 spring 26 enters the hole 27 in collar 24, and pin 28 connects toggle link 29 with crank 24' on collar 24. Pin 30 connects link 29 with crank 31 on trip collar 32, which is bifurcated and loose on shaft 33. Between the two forks of collar 32 is 30 collar 37—37', which collar is securely held to operating shaft 33 by screw 34. Spring 35 biases collar 32 clockwise, in Figure 8. Stop 36 engages projection 37' to limit the clockwise motion of collar 32.

35 Crank 31 and link 29 together form a toggle of which the pin 30 forms the center joint, and when this toggle is past center it constitutes a definite holding mechanism to withstand the bias of operating spring 26. Adjusting screw 38 40 determines the travel of this toggle past center. When crank 31 is turned counterclockwise collar 24 rotates clockwise under the bias of operating spring 26 until projection 39 reaches stop 40. Pins 41, 41 and 42, 42 connect shafts 23 and 33, respectively, with the two portions each of bars 9 and 10, preferably by non-rigid joints. Part by spring 26 extends into cup 43, which is part of housing box 21, and one end 45 of spring 50 26 projects down through a hole in cup 43. Cup 43 is securely held, as by screws 46—46 to the side of housing 21, and thereby adjustments can be made in the tension of spring 26. In Figures 4 and 5 the lateral projection on the end of a 55 switch-stick is shown at 48.

Operation is as follows:

A. The normal positions of the various members are as shown in full lines in Figures 2, 6, 7 and 8. Figure 1 shows normal conditions except that latch 15 is held by projection 20 in the position shown in Figure 5, instead of hanging freely as in Figure 6.

B. Power is supplied through each of the three dropout fuses. When overload occurs and ruptures one of the fuses, the fuse container drops in the well known manner to the fully open position shown by dotted lines in Figure 2.

C. In so falling the fuseholder develops considerable speed, and so it hits a hard hammer-blow against its respective trip member 12, thereby by rotating operating bar 10 with considerable force. This rotates operating shaft 33 counter-clockwise (see Figures 2, 6 and 8) against the bias of spring 35, and thereby it breaks the lock of the toggle holding mechanism that restrains the large operating spring 26. Thereupon spring 26 turns shaft 23 clockwise and with it grounding bar 9, so that all grounding members 11 are brought against contacts 7-7, and this blows any fuses that were intact and the circuit is fully opened.

After completion of the grounding action, the latch 15 is in the position shown in Figure 3. To reset, a switch stick end 48 is inserted in ring 17 and pushed upwardly. Since ring 17 is not directly below pivot 14, latch 15 is pushed into position shown in Figure 4, and further upward motion of the switch stick causes crank 13 to rotate and to wind up spring 26 until pivot 30 reaches the center-line position with its toggle. Spring 35 then pushes the toggle past center into its reset position as shown in Figure 8. Spring 35 also prevents the delicately set toggle lock from becoming released by vibration or other accidental causes. Screw 38 can be adjusted to alter the distance past center which the toggle can go. This makes possible a very close adjustment, and since the latch 15 is not connected with the toggle the functions of latch and toggle are independent of one another.

At the same time latch 15 has reached the position where the hole in 15 slips over projection 20, which has meanwhile been brought to its reset position. There is a slight springiness in various members, and so as pressure from the switch-stick is relaxed latch 15 becomes held by projection 20. This holds projection 20 down and holds crank 13 up. Under such conditions accidental release of grounding bar 9 is prevented. Therefore the lineman can re-fuse all fuseholders without fear that an accidental grounding operation might cause a fuse to blow in his face.

When re-fusing is completed the lineman descends, and with a switch-stick he engages ring 18 as shown in Figure 5 and pulls latch 15 away from projection 20 so that latch 15 hangs as shown in Figure 6. Thus normal conditions are restored.

We claim:

1. In a multiple conductor electric circuit, a multiplicity of fuses each comprising a dropout fuseholder and a fuselink therein, a grounding mechanism adjacent to and coordinated with the said fuses, which mechanism includes a multiplicity of grounding members interconnected and simultaneously movable, a single spring biasing all the grounding members towards grounding position, a single adjustable holding mechanism resisting the bias of said spring, a multiplicity of

interconnected trip members each operable by the dropout motion of its respective fuseholder, and members connecting the trip members with the holding mechanism, whereby the force of the dropout motion of any of the fuseholders will directly cause the release of the single holding mechanism so that the spring moves all grounding members to grounding position.

2. In combination with a multiple-conductor electric circuit which includes adjacent dropout fuses; a grounding device which includes a grounding bar and attached thereto a multiplicity of grounding members movable simultaneously into and out of contact each with its respective conductor, a single spring biasing the grounding members towards grounding position, holding mechanism to resist the bias of the spring, automatic means operable by the blowing of any one of the fuses to release the holding mechanism, and a single reset crank secured directly to the grounding bar in spaced relation from the biasing spring.

3. In combination with a multiple-conductor electric circuit which includes adjacent fuses, a grounding device which includes a grounding bar biased to rotate and with a multiplicity of grounding members secured thereto, holding means to prevent rotation of said grounding bar, a rotatable operating bar adjacent to the grounding bar, and a latch pivotally supported by the grounding bar and movable to rotate the grounding bar and engageable with the operating bar to interlock the grounding bar and the operating bar against rotation when the device is otherwise in reset condition; the said latch being then disengageable at will from the operating bar.

4. In combination with a multiple conductor electric circuit which has a multiplicity of adjacent dropout fuses each of which includes a fuseholder which drops downwardly when its fuse-link has been ruptured; a grounding device which has a multiplicity of grounding members operable simultaneously for grounding all of said conductors, said device including also biasing means to bias the grounding members towards the said conductors, and holding mechanism to restrain the said biasing means, together with a multiplicity of trip members each operable by the falling motion of its respective fuseholder and each so connected with the said holding mechanism that the energy of the falling fuseholder is directly transmitted to the said holding mechanism to release it and so to allow the said biasing means to move all grounding members into grounding contact with said conductors.

5. In combination with a multiple conductor electric circuit which includes a multiplicity of dropout fuses each with its fuseholder and each in circuit with its respective conductor; a grounding mechanism which includes a multiplicity of grounding members operable simultaneously to ground each conductor in the circuit, a single operating spring biasing all the grounding members towards the said conductors, a single holding mechanism to restrain the said operating spring, and a multiplicity of trip members each operable by the dropout motion of its respective fuseholder to release the same said holding mechanism and thereby to allow the single operating spring to move all grounding members each into grounding contact with its respective conductor.

6. In combination with a multiple-conductor electric circuit which includes adjacent fuses, a grounding device which includes a grounding bar biased to rotate and with a multiplicity of

grounding members attached thereto, a single toggle holding mechanism to prevent rotation of said grounding bar and, independent of said toggle, latch means operable at will to lock the grounding bar against rotation or to release the said lock.

7. In combination with a multiple-conductor electric circuit which includes adjacent fuses, a grounding device which includes a grounding bar biased to rotate and thereby to ground a multiplicity of conductors, a single toggle holding mechanism to prevent rotation of said grounding bar, adjustable stop means to limit the travel of the toggle past center, a relatively light spring biasing the toggle past center, and, removed from the toggle and its adjustable stop, latch means operable at will to lock the grounding bar against rotation.

8. In combination with a multiple-conductor electric circuit which includes adjacent dropout fuses, a grounding device which includes a rotatable grounding bar with a multiplicity of grounding members secured thereto, spring means biasing the grounding members towards grounding position, a single holding mechanism to resist the bias of the spring means, a rotatable operating bar adjacent to the grounding bar, a housing which partially supports the grounding bar and the operating bar and which also encloses the said holding mechanism, and a manually operable latch spaced away from the housing and operable either to interlock the grounding bar and the operating bar to prevent rotation of the grounding bar, or to release the said interlock.

9. In combination with a multiple-conductor

25

electric circuit which includes adjacent drop-out fuses, a grounding device which includes a grounding bar with a multiplicity of grounding members secured thereto and movable simultaneously into and out of grounding position, and adjacent thereto an operating bar with a multiplicity of trip members secured thereto, spring means biasing the grounding bar towards grounding position, a single toggle holding mechanism to resist the bias of the spring means when the toggle is past center, adjustable stop means to limit the motion of the toggle past center, the said trip members being respectively directly in the path of the falling fuseholders, and a connection from the operating bar to the toggle whereby the energy of any falling fuseholder is transmitted directly against the toggle to force it back past its center position and thereby to release the said spring means.

10. A grounding device as in claim 9, which includes also a relatively light spring operable to bias the toggle towards its holding position past center.
